[57] CLAIM

The ornamental design for an insect trap, substantially as shown and described.

DESCRIPTION

FIG. 1 is a front elevational view of an insect trap embodying my new design;

FIG. 2 is a right side elevational view;

FIG. 3 is a left side elevational view; and

FIG. 4 is a top plan view.

The broken lines in FIG. 1 are disclosed for illustrative purposes only and form no part of the claimed article.
